DIODE COUPLING SYSTEM

Alfred Crossley and Herbert E. Meinema, Chicago, Ill., assignors to Johnson Laboratories, Inc., Chicago, Ill., a corporation of Illinois

Application August 3, 1935, Serial No. 34,535

6 Claims. (Cl. 250—20)

The invention relates to improvements in vacuum-tube amplifying systems, and more specifically to improvements in the means for coupling the output of a vacuum-tube amplifier to the apparatus which follows the amplifier.

An object of the invention is to provide an improved means for coupling the output of a vacuum-tube amplifier to one or more diode rectifiers.

10 An additional object of the invention is to provide a coupling means for use between a vacuum-tube amplifier and one or more diode rectifiers, so arranged that its performance is substantially uniform over a wide range of frequencies.

15 A further object of the invention is to provide a simple, compact and inexpensive arrangement for efficiently coupling one or more diode rectifiers to the output of a vacuum-tube amplifier of the type intended to cover a wide range of high frequencies.

20 When vacuum-tube amplifiers are used to amplify modulated high-frequency signals, it is the usual practice to employ one or more diode rectifiers coupled to the output of the amplifier. One 25 rectifier may act as a detector or demodulator, to separate the modulation component from the carrier component of the amplified signal. A second rectifier may be used to rectify the carrier to supply a direct-current voltage for automatically 30 regulating the amplification of one or more of the amplifying vacuum tubes or for any other purpose.

If the amplifier is of the type which is tunable over a wide range of high frequencies, it is difficult 35 to couple the diode rectifiers, which are of relatively low impedance, efficiently to the output of the amplifier, which is usually of relatively high impedance. If the rectifiers are coupled to a tuned circuit, they have a serious tendency 40 to load and therefore appreciably broaden the selectivity of the tuned circuit. If, on the other hand, the rectifiers are coupled in the ordinary manner to the plate circuit of an amplifying vacuum tube, the performance usually lacks uniformity 45 over a wide range of frequencies, such as for example as the broadcast band of frequencies (550 to 1500 kilocycles per second).

The arrangement of the present invention, 50 however, permits the rectifiers to be coupled to the plate circuit of an amplifying vacuum tube in an efficient manner which provides substantially uniform performance over a wide range of frequencies. The tuned circuits of the amplifier 55 are substantially unaffected, and the means em-

ployed for accomplishing the coupling is simple, compact and inexpensive.

The present invention will be better understood by reference to the drawing, in which

Figure 1 is a schematic diagram of an embodiment of the present invention; and

Figure 2 shows the performance of a coupling system arranged in accordance with the schematic diagram of Figure 1.

Referring to Fig. 1, the plate circuit of amplifying vacuum tube 1 includes inductor 2, resistor 3, B battery 4, and self-biasing resistor 5, bypassed by capacitor 6. The screen-grid 7 of vacuum tube 1 is connected to a tap on battery 4, and is by-passed to the cathode 8 by capacitor 9. Control-grid 10 is connected to input terminal 11, and input terminal 12 is connected to the junction of battery 4 and resistor 5.

Signal diode anode 13 of vacuum tube 14 is coupled to the plate 15 of vacuum tube 1 by means of blocking capacitor 16, and is connected to the cathode 17 of vacuum tube 14 by load resistor 18. Likewise, control diode anode 19 of vacuum tube 14 is coupled to the plate 15 of vacuum tube 1 by means of blocking capacitor 20, and is grounded 25 through load resistor 21. Cathode 17 of vacuum tube 14 is grounded through resistor 22, by-passed by capacitor 23.

The modulation voltages which appear across load resistor 18 are tapped off through the resistor-capacitor filter 24, 25 and blocking capacitor 26, and made available at terminal 27. The direct-current control voltages which appear across load resistor 21 are filtered by series resistor 28 and shunt capacitor 29, and are made available at terminal 30.

Inductor 2 is so designed that, in conjunction with the associated networks, it is resonant at a frequency approximately midway between the extreme frequencies at which the system may be used, and resistor 3 is so chosen as to materially decrease the sharpness of resonance of the network. The usual values of blocking capacitors 16 and 20 and of load resistors 18 and 21 are such that they place a variable load on the plate circuit and thus produce a substantially flat gain characteristic over the frequency range, as illustrated in Fig. 2.

In operation, a portion of the high-frequency current which flows in the plate circuit of vacuum tube 1 is tapped off by capacitor 16 and rectified by diode anode 13 operating in conjunction with cathode 17 of vacuum tube 14. The steady direct-current potential which appears across load resistor 18 is blocked by capacitor 26, but the

5 pulsating voltages which correspond with the modulation are not checked by capacitor 26, and appear between terminal 27 and ground. Filter 24, 25 prevents the high-frequency voltage which 10 is present across resistor 18 from reaching the output terminal 27.

Another portion of the high-frequency current in the plate circuit of vacuum tube 1 is tapped off by means of capacitor 28 and rectified by diode 10 anode 19 operating in conjunction with cathode 17 of vacuum tube 14. The pulsating voltages, corresponding with the modulation, which are developed across load resistor 21, are prevented from reaching the control output terminal 30 by 15 filter 28, 29, but the steady direct-current potential which is present across load resistor 21 is also present between terminal 30 and ground. If a delay voltage is developed across resistor 22, no voltage will appear across load resistor 21 until 20 the amplitude of the impressed high-frequency voltage across resistor 21 exceeds the delay voltage.

In a successful embodiment of the invention, the following constants were employed:

25	Inductor 2	0.4 millihenry
	Resistor 3	5000 ohms
	Battery 4	250 volts (tapped at 100 volts)
	Resistor 5	400 ohms
30	Capacitor 6	0.1 microfarad
	Capacitor 9	0.1 microfarad
	Capacitor 16	200 micromicrofarads
	Resistor 18	1.0 megohm
	Capacitor 20	200 micromicrofarads
35	Resistor 21	1.0 megohm
	Resistor 22	1500 ohms
	Capacitor 23	0.1 microfarad
	Resistor 24	0.2 megohm
	Capacitor 25	500 micromicrofarads
40	Capacitor 26	0.02 microfarad
	Resistor 28	1.0 megohm
	Capacitor 29	0.01 microfarad

When the system is intended to operate uniformly over the usual broadcast range, the reactance of inductor 2 may be of the order of 2500 ohms at 1000 kilocycles, which is about half the value of resistor 3.

It will be understood that these constants may be varied and that various modifications, as for example the use of a single rectifier for both detection and control purposes, may be employed without departing from the scope of the invention.

Referring to Fig. 2, the ratio of the output voltage to the input voltage of the coupling arrangement is shown plotted against frequency. The input voltage is taken between grid 18 and ground, and the output voltage across resistor 21, or between diode anode 19 and ground. The 55 curve shows a slight peak at the resonant frequency of the inductor 2 and associated network, the flatness of the peak being due to resistor 3 in series with inductor 2 and the variable impedance of the entire network. The gain characteristic may be altered if desired by varying the values of the inductor 2 and resistor 3.

In a preferred embodiment, inductor 2 is of multiple-section, low-loss construction, but any suitable type of inductor may be employed without departing from the scope of the invention. 70 It will be understood that battery 4 may be replaced by any suitable direct-current source. Furthermore, vacuum tubes 1 and 14 may be replaced by a single vacuum tube containing both 75 amplifying and diode rectifying portions.

If the amplifier with which the arrangements of the present invention are to be used operates over a narrow band of frequencies, for example in the intermediate-frequency amplifier of a superheterodyne radio receiver, the inductor 2 with its associated capacitive-resistive network may be so designed that it resonates at the nominal operating frequency of the amplifier, and the sharpness of resonance may be increased to a desired degree by lowering the value of resistor 3. 10

The arrangements of the present invention are especially adapted for use in a compact radio receiver of the tuned radio-frequency type, in which it is desired to obtain automatic amplification control with a minimum effect upon the overall 15 efficiency and uniformity of performance over the broadcast band of frequencies. If a very simple and inexpensive arrangement is required, a single diode may be used to supply both the audio-frequency output and direct-current voltages for 20 control purposes. In this case, the automatic amplification control will operate without voltage delay. On the other hand, a very satisfactory delayed automatic amplification control is obtained by utilizing the arrangements disclosed herein. 25

It will be understood that the invention is not limited to the use of the control voltage for automatic amplification control. The control voltage may be used in addition or independently to control the fidelity or the selectivity of the receiver or in any other desired manner. It will also be understood that the present invention is not limited in its application to radio receivers, but that it may be employed with equal success in other types of vacuum-tube amplifiers, as well 35 as in receivers of types not herein specifically mentioned.

Having thus described our invention, what we claim is:

1. A high-frequency system including a thermionic amplifier having an anode circuit, at least one diode rectifier, an inductor and a resistor in series in said anode circuit, and a capacitor connected between a high-potential point in said anode circuit and said rectifier, said inductor and said resistor being so proportioned with respect to the load placed upon said amplifier by said rectifier that the amplification of said system is substantially constant throughout a desired range of frequencies. 40

2. A high-frequency system for operation over a range of frequencies including a thermionic amplifier having an anode circuit, at least one diode rectifier, an inductor and a resistor in series in said anode circuit, and capacitive coupling from 45 said anode circuit to said rectifier, said inductor having a natural frequency approximately at the center of said range, said resistor being so proportioned with respect to the load placed upon said amplifier by said rectifier that the amplification of said system is substantially constant throughout said range. 50

3. A high-frequency system for operation over a range of frequencies including a thermionic amplifier having an anode circuit, at least one diode rectifier, an inductor and a resistor in series in said anode circuit, and capacitive coupling from 55 said anode circuit to said rectifier, said inductor having an operating natural frequency within said range, said resistor being of such resistance as to substantially suppress the resonant peak at the natural frequency of said inductor. 60

4. A high-frequency system for operation over a range of frequencies including a thermionic amplifier having an anode circuit, at least one diode 70

- rectifier, an inductor and a resistor in series in said anode circuit and capacitive coupling from said anode circuit to said rectifier, said inductor having a natural frequency within said range, said resistor being so proportioned with respect to the load placed upon said amplifier by said rectifier that the resonant peak due to the natural frequency of said inductor is substantially suppressed.
- 5 10 15 5. A high-frequency system for operation over a range of frequencies including a thermionic amplifier having an anode circuit, at least one rectifier, an inductor and a resistor in series in said anode circuit, and a capacitor connected between a high-potential point in said anode circuit and

said rectifier, the reactance of said inductor at the middle frequency of said range being substantially one-half the resistance of said resistor.

6. A high-frequency system for operation over a range of frequencies including a thermionic amplifier having an anode circuit, at least one rectifier, and a capacitor connected between a high-potential point in said anode circuit and said rectifier, and means including an inductor and a resistor in series in said anode circuit for maintaining the amplification of said system substantially constant throughout said range. 10
